UNITED STATES PATENT OFFICE.

BENJAMIN HELLMAN, OF CHICAGO, ILLINOIS.

KEYHOLE-STOP.

No. 925,101.

Specification of Letters Patent.

Patented June 15, 1909.

Application filed January 30, 1909. Serial No. 475,231.

To all whom it may concern:

Be it known that I, BENJAMIN HELLMAN, a citizen of the United States, residing at Chicago, county of Cook, and State of Illinois, have invented certain new and useful Improvements in Keyhole-Stops, of which the following is a specification.

My invention relates to safety devices for doors.

10 The object of my invention is to provide a device of the character mentioned which will be adapted to be inserted into a key hole after the door has been locked and the key removed, the same being adapted to act in 15 the capacity of a stop so as to prevent the insertion of another key into the key hole from the opposite side of the door. It is a known fact that not infrequently are houses entered and burglarized through the aid of a 20 skeleton or master key in the possession of the burglar, it being an easy task for a burglar so provided to gain access to a house through the door thereof.

It is the object of my invention to eliminate 25 the possibility of the use of such keys for such purposes by the provision, as before stated, of a stop adapted to be inserted and securely held in a key hole.

A still further object of my invention is to 30 provide a device as stated which will be highly efficient and one which will be simple of construction, hence of low cost to manufacture.

Other objects will appear hereinafter.

35 With these objects in view my invention consists generally in a stop characterized as above mentioned and in certain details of construction and arrangement of parts all as will be hereinafter fully described and more 40 particularly pointed out in the claims.

My invention will be more readily understood by reference to the accompanying drawings forming a part of this specification, and in which,

45 Figure 1 is a front elevation of a portion of a door upon which is arranged the preferred form of my device. Fig. 2 is a side elevation thereof, portions being broken away so as to better illustrate the construction 50 of my device, and Fig. 3 is a horizontal transverse section taken on the line x—x of Fig. 1.

Referring now to the drawings 1 indicates an ordinary door which is provided with any 55 ordinary or preferred form of lock, 2 indicates

ing the casing of the latter and 3 the key hole extending through said door and lock casing.

4 indicates an elongated plate, preferably formed of cast metal, from the central portion of one of the surfaces of which perpendicularly extends a projection 5, the same being preferably formed integrally with the portion 4. Said projection 5 is so formed as to be adapted to be snugly received in a key hole of ordinary form, such as that of the 60 key hole 3 shown in the accompanying drawings, the same being of such a length as to be adapted to extend entirely through said key hole. The elongate plate portion 4 is formed at either of its extremities into a transversely 65 disposed perforated ear 6. The ears 6 are adapted, when the portion 5 of the device is in position in the key hole of the door, to snugly rest in slots 7 provided in the tubular portions 8 of bracket members 9, the latter 70 being fixed to the inside surface of the door 1 at either side of the key hole therein preferably by means of screws 10. The perforations provided in said ears 6 of the plate portion 4 are adapted when said ears are in 75 position in said slots 7, to be in alinement with the passage through the tubular portions 8, removable lock pins 11 extending through the tubular portions 8 and the 80 perforated ears 6 of the member 4, obviously 85 facilitating securely holding the latter in position upon a door. An integral ear 12 projecting from the central portion of the front face of the plate portion 4 acts in the capacity of a finger piece, the same facilitating 90 the ready arrangement upon or removal from a door, of my device.

As shown in Fig. 3 the plate portion 4 is preferably transversely channeled in construction, so as to accommodate the projecting key hole guard plate 13 ordinarily provided upon a door. However, such provision is not essential, as it is obvious that the brackets 9 could be so formed or could be spaced at such a distance from the inside surface of the door as to accomplish the same purpose.

By the provision of a device of such construction it is obvious that upon turning the lock and removing the key therefrom, the former may be inserted into the key hole and may be securely held in place therein, thereby preventing the insertion of a key from the opposite side of the door and hence obviating the possibility of unlocking the door until 110

said device is removed, which removal there-
of is only possible from the inside.

While I have shown what I deem to be the
preferable form of my invention, I do not
5 wish to be limited thereto, as there might be
many changes made in the details of con-
struction and arrangement of parts without
departing from the spirit of my invention.

Having described my invention what I
10 claim as new and desire to secure by Letters
Patent is:

1. A device of the class described, comprising
an elongated plate, a projection forwardly
15 extending from said plate and adapted
to fit snugly within a key hole, and means
at each end of said plate for detachably lock-
ing the same upon a door to close the key
hole, substantially as described.

2. A device of the class described, comprising
20 a plate, a projection forwardly extending
from said plate adapted to be snugly received
in and extend substantially the entire length
of a key hole, transversely disposed ears
25 formed at the extremities of said plate, and
means adapted to engage said ears whereby
said plate may be removably secured to a
door, substantially as and for the purpose
specified.

3. A device of the class described, comprising
30 a plate, a projection forwardly extending
from said plate adapted to be snugly received
in and extend substantially the entire length
of a key hole, transversely disposed ears
35 formed at the extremities of said plate,
means adapted to engage said ears whereby
said plate may be removably secured to a
door, and a finger piece projecting from said
plate, substantially as and for the purpose
specified.

40 4. In a device of the class described, the
combination with a door, of a plate, a projec-
tion forwardly extending from said plate
adapted to be snugly received in and extend
substantially the entire length of the key hole
45 in said door, transversely disposed ears
formed at the extremities of said plate, slot-
ted tubular brackets provided upon said
door adjacent to said key hole, the ears of
said plate being adapted to engage the slots

in said brackets, and lock pins adapted to ex-
50 tend through the tubular portions of said
brackets and the perforations in said ears,
substantially as and for the purpose speci-
fied.

5. In a device of the class described, the
combination, with a door, of an elongate
plate, a projection forwardly extending from
said plate adapted to be snugly received in
and extend substantially the entire length of
60 the key hole in said door, transversely dis-
posed ears formed at the extremities of said
plate, slotted tubular brackets provided upon
said door adjacent to said key hole, the ear
formed extremities of said plate being adapt-
65 ed to rest in slots in said brackets, lock pins
adapted to rest in and extend through the
tubular portions of said brackets and the per-
forations in said ear formed extremities of said
plate, and a finger piece projecting from the
60 central portion of said plate, substantially as
and for the purpose specified.

6. In a device of the class described, the
combination, with a door, of an elongate
transversely channeled metal plate, the chan-
nel in said plate being adapted to accommo-
date the key hole guard plate of said door, a
projection forwardly extending from said
75 plate adapted to be snugly received in and
extend substantially the entire length of the
key hole in said door, transversely disposed
ears formed at the extremities of said plate,
slotted tubular brackets provided upon said
80 door at either side of said key hole, the ear
formed extremities of said plate being adapt-
ed to rest in slots in said brackets, and lock
pins adapted to rest in and extend through
85 the tubular portions of said brackets and the
perforations in said ear formed extremities of
said plate, substantially as and for the pur-
pose specified.

In testimony whereof I have signed my
90 name to this specification in the presence of
two subscribing witnesses.

BENJAMIN HELLMAN.
